CLAIM

The ornamental design for a bottle for cosmetics, as shown and described.

DESCRIPTION

FIG. 1 is a top perspective view of a bottle for cosmetics, showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a bottom perspective view thereof; and,
FIG. 9 is another top perspective view showing the head portion of the bottle for cosmetics in a retracted position.
The broken lines are shown for illustrative purposes only and form no part of the claimed design.
